UNITED STATES PATENT OFFICE

RICHARD FITZ POWER, OF HAMPSTEAD, LONDON, ENGLAND, ASSIGNOR TO MORLAND & IMPEY LIMITED, OF BIRMINGHAM, ENGLAND

DEVICE FOR OPERATING LOOSE-LEAF BINDERS, BOOKS, CARD TRAYS, AND THE LIKE

Application filed October 25, 1928, Serial No. 314,970, and in Great Britain December 24, 1927.

This invention relates to mechanical devices for operating loose leaf books or binders, card trays, or the like, and has especial reference to the operation of the binders described in U. S. A. Patent No. 1,790,441, January 27, 1931, for the purpose of releasing and resecuring leaves contained in the binder.

The binder described in Patent No. 1,790,441, employs a particular form of leaf having on one edge an open-faced recess or recesses with undercut ends, and the binders essentially comprise anchoring members adapted to occupy the undercut ends of the recesses under spring pressure to secure the leaves, together with binding plates gripping the leaves in a direction at right-angles to their plane, also under spring pressure.

In connection with binders of this character, a device was proposed in U. S. A. patent specification No. 1,677,461, July 17, 1928, in which the binder was placed when required to be operated for removal, or replacement, of the leaves, such device including a handle controlling abutment plates which served to perform the simultaneous operation of opening the binding plates and disengaging the anchoring members necessary to release the leaves.

In the case of large binders, and large leaves, or of cards in trays, it was found rather difficult to reassemble or to insert leaves, as some were apt to slide over the mechanism, or to bulge, so that a new leaf or leaves might not be properly placed on the anchoring bars, or tray bottom, which led to the cards or sheets being liable to be bent or spoiled.

The present invention has for its object to provide for the ready insertion of the leaves in the binder, tray, or the like, and to ensure that the remaining leaves retain their correct disposition while freed so that their reseurement presents no difficulty.

Broadly, the present invention consists in the provision, in combination with a device for mechanically operating the loose leaf binders, or trays, of leaf-supporting means, or card-supporting means operative on the leaves, or cards, being released to position them ready for rebinding, and simultane-

ously to prevent their collapse or sliding over the mechanism of the device.

Although the device in accordance with the present invention may with advantage, and either with or without modification, be used for the operation of card trays, or of loose leaf binders of other character, for the purpose of simplifying the following description the device will be hereinafter described for more particular application to loose leaf binders of the character in question, that is, as described in U. S. A. Patent No. 1,790,441, January 27, 1931, wherein the binding is effected by expanding anchoring members into recesses in the sheets and contracting binding members to draw the sheets tightly together.

According to one embodiment the leaf-supporting means comprise plates positioned so as to lie transversely below the recessed edges of the leaves of the binder when the latter is mounted in the operating device, these plates being connected with the operating mechanism of the device in such manner that on the abutment plates engaging the anchoring members and releasing the leaves, a vertical movement is given to the supporting plates so that their upper faces, each formed as a serrated plate or platform, rise into abutment with the lower edges of the leaves, and thus retain them in the position required; the serrated surfaces mentioned are provided in order to ensure that the edges of the sheets shall not slip on the rising plates, and so that they remain in position and do not slide, and are thus in correct alignment when the device is operated to resecure the leaves in the binder.

The invention will be further described with reference to the accompanying drawings which illustrate by way of example one mode of embodying the invention, and in which:

Fig. 1 is a plan view of the release stand constructed according to U. S. A. patent specification No. 1,677,461, and embodying leaf-supporting means according to the present invention;

Fig. 2 is a section on the line II-II of Fig. 1 illustrating the disposition of the leaves of a binder in regard to the leaf-supporting

means, on the binder being positioned in the stand for the purpose of releasing the leaves;

Fig. 3 is a section on the line III—III of Fig. 2 looking from the right, showing the arrangement of the leaf-supporting means, and in dot-and-dash lines the position occupied thereby on release of the leaves from the binding mechanism, and

Figs. 4, 5 and 6 are detail views illustrating the manner in which the release mechanism is adapted to automatically effect movement of the leaf-supporting means and the serrated surface provided on the upper face of the leaf-supporting means for the purpose of ensuring correct alignment of the leaves on operation of the device to reposition the leaves in the binder, Fig. 4 being a sectional view of the leaf-supporting means and associated release mechanism; Fig. 5 a perspective view of the underside of the leaf-supporting means; and Fig. 6 a perspective of the upper operative face of the leaf-supporting means illustrating its serrated upper surface.

Referring now to the drawings, but first more particularly to Figs. 1, 2 and 3, 1 represents a release stand adapted for operation on binders such as described in U. S. A. Patent No. 1,790,441, January 27, 1931, comprising anchoring members adapted under spring pressure to occupy the undercut ends of recesses provided on one edge of the leaves together with binding plates gripping the leaves, also under spring pressure, in a direction at right-angles to their plane.

The release stand includes an operating handle 2 controlling abutment plates 3, 4, and 5 and 6 respectively, the abutment plates 3 and 4 outwardly engaging the anchoring members of the binder and moving inwardly, and the abutment plates 5 and 6 inwardly engaging the binding plates and simultaneously moving outwardly to effect release of the leaves, such as 7, positioned on the binder.

Guide walls 8 and 9 are provided on the release stand which serve to ensure that a binder placed on the release stand 1 will occupy the position in which the abutment plates 3, 4, and 5, 6 respectively engaged the anchoring members and binding plates of the binder.

Reciprocation of the abutment plates 3, 4, and 5, 6 is obtained from the handle 2 in the manner described in U. S. A. patent specification No. 1,677,461, operation of the handle 2 serving to rotate a disc 10 coupled to the said abutment plates by means of a system of links, movement of the handle in one direction effecting movement of the abutment plates 3, 4 and 5, 6 such as will release leaves such as 7 secured by a binder positioned on the release stand 1, and movement of the handle 2 in the opposite direction effecting such a movement of the abutment plates as will permit the binder to assume a position of resecurement

for the leaves.

The abutment plates 3 and 4 are mounted on guides 11 and 12 sliding in suitable beds or bearings 13 and 14, and the abutment plates 5 and 6 have guide members 15 and 16 likewise running in beds or bearings 17 and 18, such beds or bearings being suitably mounted in the frame of the release stand 1, preferably on an aluminium subframe 19 suitably mounted in the stand 1, the body of which is preferably of mahogany or other polished hard wood.

The leaf-supporting means according to the present invention are constituted in the example illustrated by horizontally disposed plates 20 and 21 adapted to reciprocate vertically in the beds or bearings 13, 14, which for this purpose are each provided with a vertical recess or guide 22 and 23 respectively, and blocks or plungers 24 and 25, on which the leaf-supporting plates 20, 21 are respectively mounted, slide in said recesses or guides 22, 23, so that the leaf-supporting plates 20 and 21 are permitted vertical movement but are free from any tendency to rock laterally.

Each block or plunger 24, 25, is provided with a cam slot 26, and the abutment plate guides 11 and 12 which pass horizontally through the bearings 13 and 14 are provided with pins 27, 28, engaging said cam slots 26 and are arranged on inward movement of the abutment plates 3 and 4 at the instance of the handle 2 for the purpose of releasing the leaves secured on a binder mounted in the release stand 1, to raise the leaf-supporting plates 20, 21, to a position in which they support the leaves such as 7 of the binder, retention of correct alignment in the leaves being enhanced by reason of the upper surfaces of the supporting plates 20, 21 being provided with transverse serrations 29 which engage the lower edges of the leaves.

To ensure that the leaves are free to be supported by the plates 20, 21, on these being elevated to supporting position, the cam slots 26 are shown arranged with a horizontal portion 30, the initial movement of the abutment plates 3, 4 and 5, 6, thereby occurring before any elevation is imparted to the leaf-supporting plates 20, 21, whereby the anchoring members and binding plates of the binder on which the said abutment plates operate have achieved the necessary preliminary movement to release the leaves, the pins 27 and 28 then acting on the inclined faces of the slots 26 of the guide blocks 24, 25, and effecting the desired elevatory movement of the leaf-supporting plates 20 and 21 into their leaf-supporting position.

The normal or out-of-use position of the stand 1 is illustrated in Figs. 1 and 2, the leaf-supporting plates 20 and 21 in this position lying at the bottom of their travel, and when it is required to operate the binder for the purpose of releasing the leaves thereof, such binder is placed in the release stand 1 and is

guided into its correct operative position by means of the side walls 8 and 9 of the release stand, that is, with the abutment plates 3 and 4 in outward engagement with the inwardly-to-be-drawn anchoring members of the binder, and the other abutment plates 5 and 6 in inward engagement with the outwardly-to-be-moved binding plates.

The operating handle 2 is then moved in the direction of the arrow in Fig. 1, and, due to the pins 27, 28, moving in the horizontal portion 30 of the slots 26, a preliminary movement of the abutment plates is effected releasing the leaves of the binder, further movement of the handle 2 being required to cause the pins 27, 28, to engage the cam portion 26 of the slots, whereat the leaf-supporting plates 20, 21 are elevated into the desired position of support for the released leaves 7 of the binder. Leaves can then be removed or replaced, or leaves already on the binder repositioned at the will of the operator, and this operation is enhanced by the serrated upper surfaces 29 of the supporting plates 20, 21, which further prevent unwanted displacement of the leaves 7.

On the desired repositioning being obtained, the operator returns the handle 2 to normal position and the reverse operation takes place in the respective parts, preliminary movement of the handle 2 on the return stroke effecting downward movement of the leaf-supporting plates 20, 21, so that the leaves 7 drop into their desired position on the anchoring members of the binder which are moving outwardly, complete outward movement of the anchoring members being accompanied by simultaneous inward movement of the binding plates such that on the handle 2 of the release stand 1 being returned to the position illustrated in Figs. 1 and 2, the desired reseurement of the leaves 7 within the binder is accomplished.

As an alternative arrangement spring-controlled plates can be operated by suitable mechanism to rise when the springs are released, for example, to correspond with the required release movement of the operating handle.

It will be understood that although the invention has been described with more especial reference to devices for the mechanical operation of binders including anchoring members and binding plates, that is substantially in accordance with U. S. A. Patent No. 1,790,441, January 27, 1931, the invention is also applicable to devices for the mechanical operation of binders of other character.

What I claim is:

1. A device for mechanically operating loose leaf holding apparatus comprising leaf-supporting means associated with the leaf-release mechanism of the device, normally out of leaf-supporting position and operable automatically from the leaf release mecha-

nism on release of the leaves in the binder to assume a position of leaf support.

2. A device for mechanically operating loose leaf binders, comprising a pair of horizontal plates associated with the leaf release mechanism of the device and reciprocable vertically by the release mechanism on release of the leaves to assume a position of support for the leaves.

3. A device for mechanically operating loose leaf binders, comprising a pair of horizontal plates, guide blocks having cam slots connected to each of said plates, and pins on the leaf-release mechanism of said device engaging said slots, and operable automatically by the leaf-release mechanism on release of the leaves to move said plates to a position of support for the leaves.

4. A device for mechanically operating loose leaf binders, comprising a pair of horizontal plates, guide blocks having cam slots connected to each of said plates, reciprocable vertically in regard to said device, and pins on the leaf-release mechanism of said device engaging said slots and adapted on release of the leaves to simultaneously elevate said plates to a position of leaf support.

5. A device for mechanically operating loose leaf binders comprising a pair of horizontal plates having serrated upper surfaces, and means for operatively connecting said plates with the leaf-release mechanism of the device to cause said plates to assume a position of leaf support on release of the leaves in the binder.

6. A device for mechanically operating loose leaf binders comprising a pair of horizontal plates having serrated upper surfaces, a guide block having a cam slot on the underside of each plate, and pins on the leaf-release mechanism of said device engaging said slots and operating said blocks automatically on release of the leaves to elevate said plates to a position of support for the leaves.

7. A device for mechanically operating loose leaf binders in which the leaves are secured by anchoring members adapted to occupy undercut ends of recesses in the leaves, under spring pressure, comprising a pair of leaf-supporting plates associated with the leaf-release mechanism of the device and operable automatically from the leaf-release mechanism on release of the leaves by withdrawal of the anchoring members, to assume a position of support for the released leaves.

8. A device for mechanically operating loose leaf binders in which the leaves are secured by anchoring members adapted to occupy undercut ends of recesses in the leaves under spring pressure, comprising a pair of horizontal plates associated with the leaf-release mechanism of the device, guide blocks connected to each of said plates having cam slots, and pins on said mechanism engaging

- said slots and adapted on release of the leaves by said release mechanism by withdrawal of the anchoring members to elevate said plates to a position of leaf support.
- 16 9. A device for mechanically operating loose leaf binders in which the leaves are secured by anchoring members adapted to occupy undercut ends of recesses in the leaves under spring pressure, comprising abutment plates adapted to outwardly engage the anchoring members of the binder, guide members for said abutment plates, and pins on said guide members, a pair of leaf-supporting plates, guide blocks on said leaf-supporting plates having cam slots, engaged by said pins and operable upon said abutment plates' engaging said anchoring members to release the leaves, to elevate said leaf-supporting plates to a position of support for the leaves.
- 17 10. A device for mechanically operating loose leaf binders in which the leaves are secured by anchoring members adapted to occupy undercut ends of recesses in the leaves under spring pressure, comprising a frame adapted for the receipt of a loose leaf binder, abutment plates adapted to outwardly engage the anchoring members of the binder, guide members for said abutment plates and pins on said guide members, a pair of leaf-supporting plates, guide blocks on said leaf-supporting plates, having cam slots engaged by said pins, an operating handle linked to said abutment plates causing them to engage the anchoring members of the binder and release the leaves, and simultaneously to effect elevation of said leaf-supporting plates to a position of support for the leaves.
- 18 11. A device for mechanically operating loose leaf binders in which the leaves are secured by anchoring members adapted to occupy undercut ends of recesses in the leaves under spring pressure, comprising abutment plates adapted to outwardly engage the anchoring members of the binder, guide members for said abutment plates, and pins on said guide members, a pair of leaf-supporting plates with serrated upper surfaces, guide blocks on the lower surfaces of said leaf-supporting plates, having cam slots engaged by said pins, and operable upon said abutment plates' engaging said anchoring members to release the leaves, to elevate said leaf-supporting plates to a position of support for the leaves.
- 19 12. A device for mechanically operating loose leaf binders in which the leaves are secured by anchoring members adapted to occupy undercut ends of recesses in the leaves under spring pressure with spring-pressed binding plates gripping the leaves at right-angles to their plane, comprising abutment plates arranged to simultaneously engage said anchoring members and said binding plates, and thereby to release the leaves, guide mechanism for said abutment plates, leaf-
- supporting plates connected with the guide mechanism of said anchoring members in such manner as to assume a position of support for the leaves on movement of said plates to release the leaves from the anchoring members.
- 20 In testimony whereof I affix my signature.
RICHARD FITZ POWER.
